UNITED STATES PATENT OFFICE.

DOMINICK PECCERILLO, OF NEW HAVEN, CONNECTICUT.

CONTROL SYSTEM.

Application filed January 21, 1926. Serial No. 82,748.

Fig. 1 is a diagrammatic view of a control system embodying my invention, the parts being shown in the positions due them when the car is at rest, and the master-control 60 switch is in its "off" position.

Fig. 2 is a broken view, corresponding to Fig. 1, with the parts in the positions due them when the car is traveling in the "down" direction, and when it is desired to effect an 10 automatic stop at the next floor-level.

Fig. 3 is a view, corresponding to Fig. 2, but showing the parts in the positions due them when it is desired to continue the downward travel past a floor-level, or to start 15 downward, after having stopped.

My invention relates to motor-control systems, and particularly to that class of control systems which are employed in connection with elevators, hoists, and similar 20 apparatus.

The object of my invention is to provide means under the control of a single, manually-operable master-switch, whereby the operator is enabled, at his option, to effect the 25 automatic stoppage of the car at any given floor-level, to pass the given floor, or to start therefrom, after a stop has been made.

With this general object in view, my invention consists in a control-system characterized by having a manually-operable master-switch for controlling the movement of the car, which, when in one position, will divert a control-current through an automatic switch, operable by the movement of 35 the car, and when in another position, will render the said automatic switch ineffective by causing the control-current to flow through an independent channel, whereby the operator is enabled, at his option and by 40 means of a single handle, to effect the automatic stoppage of the car at any given floor-level, to pass the given floor, or to start therefrom, after a stop has been made.

My invention further consists in certain 45 details of construction and combinations of parts as will be hereinafter described and particularly recited in the claims.

I am aware that it has been proposed to 50 effect the automatic stoppage of an elevator car by means of an automatic switch operated by the movement of the car, but such a switch cannot be rendered ineffective at the will of the operator by means of a master-switch, but requires the manipulation of a 55 separate element to cut it out of action, in order to enable the operator to pass a given

floor, or to start therefrom, after a stop has been made. The annoyances and difficulties of operation inherent in such a system are obviated under my invention, as will hereinafter appear.

In the embodiment of my invention herein shown, the driving motor consists of an armature 10 and a field-magnet-winding 11 which latter is operatively connected to a 65 positive line-conductor 12 and to a negative line-conductor 13 in the customary manner. A resistor 14 is interposed in the circuit through the armature, during the starting period. This resistor is cut out of the armature circuit shortly after the start of the motor by a slow-acting automatic switch 15, also in the usual manner.

Current is sent through the armature 10 in one direction, as, for instance, to cause the 75 motor to drive the elevator upward by an automatic switch 16 having double contacts, as shown, and operated by what I will call the "up-control" solenoid 17. Current is also sent through the armature, but in the opposite direction, by an automatic switch 18 having double contacts as shown, and operated by a solenoid 19, which I shall designate the "down-control" solenoid. One terminal of each of the solenoids 17 and 19 is 80 connected by a conductor 20 to the negative line-conductor 13. The opposite terminal of the up-control solenoid 17 is connected by a conductor 21 to an up-control contact 22 of the master-control switch 23, which is 85 mounted in the elevator car, generally designated by the numeral 24, and moving in a shaftway 25, while the remaining terminal of the down-control solenoid 19 is connected by a conductor 26 to a down-control contact 90 27 of the master-control switch 23.

The positive line-conductor 12 extends to the master-control switch, where it supplies current to two contacts 28 and 29. The said positive line-conductor 12 is also connected, 100 as at 30, to the pivotal blade 31 of an automatic switch, generally designated by the numeral 32, and mounted on the exterior of the car 24, and including a contact 33 connected by a conductor 34 to a contact 35 of 105 the master-control switch.

The switch-blade 31 of the automatic switch 32 is normally maintained in engagement with the contact 33 by a spring 36, and is provided with a roller 37 adapted to engage cams located adjacent each floor-level, 110 only one of which, however, is shown in the

drawings, and is designated by the numeral 38.

The master-control switch 23 includes a controller-arm 39 having a handle 40 at its outer end, and pivotally mounted as at 41. The inner end is formed with a switch-blade 42 adapted to engage with the contacts 22, 27, 28, 29, and 35.

Assuming that the car is traveling in the "down" direction and that the operator wishes to stop at the floor-level 43, he will move the controller-handle 40 into the position in which it is shown in Fig. 2, whereby the motor-control circuit, which causes the 10 down-control solenoid 19 to move the switch 18 so as to cause the motor to rotate in the proper direction for the down-travel of the car, will flow from the positive line-conductor 12, through the blade 31 of the automatic switch 32, through the contact 33 thereof, and thence through the conductor 34 to the contact 35, through the master-control switch-blade 42, to the contact 27, through the conductor 26, thence through 15 the conductor 25 to the negative line-conductor 13.

With the master-control switch in this position, and the car traveling in the "down" direction, as described, shortly before the 20 car reaches the floor-level 43, the roller 37 of the switch-blade 31 will engage the cam 38 and disengage the said blade from the contact 33, and hence shut off the supply of current to the down-control solenoid 19, permitting its automatic switch 18 to open and thus effect the stoppage of the motor, and hence the car.

Now, if after the automatic stoppage just described, the operator wishes to start the 25 car again in the "down" direction, he has merely to move the controller-handle 40 into the position in which it is shown in Fig. 3, whereby the motor-control circuit will flow from the positive line-conductor 12, through the contact 29, master-control switch-blade 42, contact 27, conductor 26, to the down-control solenoid 19, and thence to the negative line-conductor 13, with the effect of energizing the down-control solenoid 19, and causing its automatic switch 18 to close a circuit through the armature and thus cause the motor to drive the car in the "down" 30 direction, and to continue to do so, so long as the controller is held in this position, or until the car reaches the limit of its downward-travel.

If, upon approaching the floor-level 43, the operator has no desire to stop, it will be understood that, by moving the controller 35 into the position shown in Fig. 3, he may thereby render the automatic switch 32 ineffective and cause the car to continue its downward-travel past this floor.

To effect the automatic stoppage of the car when it is traveling in the "up" direc-

tion, the operator would move the master-switch control-handle 40 partway to the right of the "off" position so that the switch-blade 42 would engage the contacts 22 and 35, whereby the up-control solenoid 17 would be energized, so as to operate the switch 16 to close a circuit through the armature 10 of the motor in a direction opposite from that in which it flows when it is desired to have the car travel in the "down" direction. 75 This circuit would flow from the line-conductor 12 through the switch-blade 31, contact 33, conductor 34, contact 35, switch-arm 42, contact 22, conductor 21, through the solenoid 17, and thence through the conductor 20 to the negative line-conductor 13. 80

To start the car in its upward travel, after an automatic stoppage, or to pass any given floor after having started, the controller-arm 39 is moved to the limit of its travel to the right, so that its switch-blade 42 engages the contacts 22 and 28 of the master control-switch, whereby the up-control solenoid 17 will be energized by a circuit flowing from the positive line-conductor 12, through contact 28, switch-blade 42, contact 22, conductor 21, up-control solenoid 17, and thence by the conductor 20 to the negative line-conductor 13. 85

It will be seen from the foregoing that, under my invention, a single master-switch 90 enables the operator, at his option, to effect the automatic stoppage of the car at any given floor, to pass the given floor, or to start therefrom after a stop has been made 100 in either the "up" or "down" direction. 95

While the embodiment of my invention herein shown includes solenoids interposed in the motor-control circuit, I wish to have it understood that I do not limit myself to the 105 employment of such elements, since there are a wide variety of control circuits adaptable for use with my improved control system.

I claim:

1. A control system, including a car, a motor therefor, an automatic switch operable by the movement of the said car, a master-control switch carried by the said car and manually operable by means of a 115 single handle, which, when in one position, causes a motor-control current to flow through the said automatic switch, which is thereby placed in series with the said master-control switch, and when in another 120 position, to render the said automatic switch ineffective by causing the control-current to flow through independent channels.

2. A control system, including a car, a motor therefor, an automatic switch operable by the movement of the said car, a master-control switch carried by the said car and manually operable by means of a single handle, and a control-circuit governed by the said master-switch and by means of 130

which it may connect itself in series with the said automatic switch, and including an up-control solenoid and a down-control solenoid, and having two channels of flow, 5 one of the said channels including the said automatic switch, and the other being independent thereof.

3. A control system, including a car, a motor therefor, an automatic switch operable by the movement of the said car, a master-control switch carried by the said car and manually operable by means of a single handle, and having contacts, one of the said contacts being connected to the 15 motor for causing it to drive the car in one direction, another of the said contacts being connected to the said motor for causing it to drive the car in the opposite direction, two control-circuit channels, one of the said 20 channels including the automatic switch, and the other being independent thereof, and means operated by the handle of the master-control switch for connecting either of said contacts with either of the two control-circuit channels, whereby the said master-control switch has capacity for connecting itself in series with the said automatic switch at the option of the operator.

4. A control system, including a car, a motor therefor, an automatic switch operable by the movement of the said car, a master-control switch carried by the said

car and manually operable by means of a single handle, and having contacts, one of the said contacts being connected to an up-control solenoid, another of the said contacts being connected with a down-control solenoid, two control-circuit channels, one of the said channels including the said automatic switch, and the other being independent thereof, means operated by the handle of the master-control switch for connecting either of said contacts with either of the said control-circuit channels, whereby the said master-control switch has capacity for connecting itself in series with the said automatic switch at the option of the operator.

5. A control system, including a car, a motor therefor, an automatic switch operable by the movement of the said car, a master-control switch carried by the said car and manually operable by means of a single handle, a control-circuit governed by the said master-switch and having two channels of flow, one of the said channels including the said automatic switch, and the other being independent thereof, whereby the said master-control switch has capacity for connecting itself in series with the said automatic switch at the option of the operator.

In testimony whereof, I have signed this specification.

DOMINICK PECCERILLO.
